PUMP

Thomas E. Brinton, Cedar Falls, Iowa

Application October 9, 1941, Serial No. 414,295

3 Claims. (Cl. 103—195)

This invention relates to the pumping of water or other liquids from below ground to the surface, or one level to another, and is adapted for use with a pressure tank, not shown, pipe line or open tank.

The objects of this invention are as follows:

First: to relieve the lifting stroke from all pressure, resulting in a simple gravity lift even where a pressure tank is used.

Second: to utilize, for working purpose, the gravity force produced by the weight of the falling pump-rod on the down stroke.

Third: to provide hydraulic means which eliminate the jarring shock of the reciprocating action.

Fourth: to prevent the waterlogging of the tank in a pressure system.

Fifth: to make more efficient use of the power applied.

These objects are accomplished by the use of a balancing cylinder on the pump, and the combination upon the pump rod of a plunger fixed to the rod with a valvular device mounted movably upon the rod below the plunger, together with accessory devices associated with said valvular device. There is included an intermediate delivery conduit to receive and deliver a stream of water or other liquid during the operation of the pump, whereby the pump rod when descending may utilize its own gravity for facilitating the operation of the pumping stroke, also relieving the cylinder located in the well from all pressure duty.

The above considerations thus enhance the utility of the pump, and effect a saving of power resulting from the smoother action of its elements.

In the drawing, Fig. 1 is a side elevation of my improved pumping device, with parts removed or cut away. Fig. 2 is a longitudinal axial section of Fig. 1. Fig. 2a is an enlarged longitudinal central section lower valve.

The numeral 1 denotes the barrel or casing of the upper part of the pump, the casing 1 having a cap 3 threaded removably thereon and somewhat contracted at its upper end, with the upper end threaded to receive a centrally apertured bearing.

A plunger rod 16 traverses the bearing 4 for reciprocation therethrough, the rod being broken away above the bearing 4, but it will be understood that any appropriate means may be connected operatively to said rod for actuating it. The cap 3 may have an outlet tube 5, threaded horizontally thereinto laterally, and said tube 5

has an outward thread to seat thereon an angle-spout 6, which may be turned up or down as desired to prime, or drain, in case of damage to packings.

5 The cylindrical body 1 has a member 7 inwardly threaded to seat it upon an external thread on the lower outer wall of said body, and said member has at its lower and outwardly directed flange with opposite upwardly directed and interiorly threaded studs to seat the cap screws 15 therethrough, to project downwardly therefrom.

The numeral 8 denotes a downwardly extending member of the pump body positioned below and 15 spaced from the member 7 and having an outward rim, said rim having interiorly threaded opposite holes to seat therethrough the screws 15 which also traverse downwardly directed bosses on the rim. The numeral 12 (see Fig. 1) denotes a rubber sheet clamped between the body part 8 and the flange 7 to prevent leakage.

Within the hollow 8a is a bell-shaped valve cage 23 surrounding the pump rod 22, with openable lower end, and the lower end face is narrowed without to seat around it a conical packing ring 25.

The inner face of the lower part of the cage member is threaded to receive within it, valve seat 24 with its lower part widened to support the packing ring 25. The lower body 8 has a thickened wall.

30 Within the valve cage 23 is a metal valve 27, which surrounds pump rod 22, and is loosely positioned upon the top of valve seat 24. Valve 27 has at its upper end an outwardly widened shoulder resting upon a composition ring 26.

35 The upper face of member 27 has a concentric hollow in which is an annular ring 28 with vertical side wall inturned. Fig. 2a is an enlarged 40 representation of the member 27 with the ring 28 therein, which has an upwardly directed side wall inturned at the top. A composition ring with upwardly directed outer wall 29 is fitted within the member 28 and secured by the in-turned part thereof, and the ring also has an upturned inner ring 29a and is pressed into valve 27.

45 Due to the action of packing ring 29 to hug pump rod 22 on upstroke it will rise to top of valve cage 23, allowing liquid to fill vacuum chamber 22a. On the down stroke, valve 27 will move with pump rod till ring 26 rests on valve seat 24, thus preventing any pressure on well pipe or lower cylinder, and discharges contents through 50 passage 8f. The packing ring 26 is held in place

by a locking ring 26a, resiliently. As shown in Fig. 2 the ring 25 packs against the lower end of the member 23.

A bushing 9 has an inner threaded connection with the threaded upper end of the well pipe 10, shown cut away, but it is directed downwardly into a source of liquid content.

Referring to Fig. 2, the chambered part 8 has a lateral passage 8f into a second chamber 8e in an extended or widened part, and an exteriorly threaded plug 13 with concaved top 13a, is fitted in the apertured bottom of the chamber 8b with interior hollow 8e, which hollow at the top is narrowed, slightly, to register with openings 8d, 11b, and 7a in casting 7, which seats the lower end of a street ell therein. Outlets can be taken off from 14 or 13 or both, thus making possible to have a fresh water outlet in connection with a pressure system.

The upper end 21a of the pump rod 22 is threaded around the part having an interior thread, and is seated in a hollow seat in plunger 17, which is threaded on plunger rod 16. This in turn makes a swivel seat 21 for the pump rod. One or more packing cups are fitted slidably within the liner tube 2, which latter extends downwardly from within the tubular body 1 and cap 3, to terminate below at part 11a. The upper part of plunger 17 being widened outwardly to compress the inturned upper end of the packing cup 18, an externally channelled spacer member 19, is placed above packing cup 21 and bushing 20, and is threaded on to plunger 17 to produce a tight seal to prevent leakage.

Channelled member 19 and bushing 20 on the suction stroke will allow the packing cups to collapse and a small amount of air to pass by and enter the liquid being pumped, which prevents a waterlogged pressure tank. When bushing 9 is removed with a two inch pipe in well, and a flush cap cylinder by removing cap 3 entire, work parts 16, 17, and valve cage 23 can be removed or installed without disturbing other parts in any way.

I claim:

1. In a pump of the character described, a tubular housing with an apertured top closure, a reciprocating pump rod traversing said closure and housing, an imperforate piston fixed on the upper inner part of the rod, an upwardly cupped rigid member positioned below and in spaced relation to the lower end of the housing, and having a central opening traversed by said rod, a depending pipe seated in said opening, a rigid plate mounted upon said cupped member, an elastic member and the rigid plate being clamped peripherally together between the adjacent faces of the housing and the cupped member, an internal housing member, tubular and having a plurality of side wall apertures therein, and rigidly removably mounted between the bottom part of the cupped member and said rigid plate, a flanged tubular valve member slidably mounted on the pump rod within the housing member, an elastic ring mounted on the valve member contacting its flange, said valve member being removably engaged with said internal housing member, elastic means mounted on the valve member and having an upturned inner rim to slidably yieldably engage the pump rod, and a delivery spout device in communication with the internal housing member, with a turnable device therefor.

2. In a pump of the character described, a tubular housing with an apertured top closure, a reciprocating pump-rod traversing said closure

and housing, an imperforate piston fixed on the upper inner part of the rod, an upwardly cupped rigid member positioned below and in spaced relation to the lower end of the housing, and having a central opening traversed by said rod, a depending pipe seated in said opening, a rigid plate mounted upon said cupped member, an elastic member mounted upon said rigid plate, the rigid plate having a plurality of apertures in communication with the cupped member, and also having an aperture traversed by said rod, the elastic member and the rigid plate being clamped peripherally together between the adjacent faces of the housing and the cupped member, an internal housing member, tubular and having a plurality of side wall apertures therein, and rigidly removably mounted between the bottom part of the cupped member and said rigid plate, a flanged tubular valve member slidably mounted on the pump rod within the housing member, an elastic ring mounted on the valve member contacting its flange, the lower part of said internal housing member being recessed outwardly, a downwardly coned rubber ring mounted in the recess, said flanged valve member having an upwardly open circular cavity around the pump rod, a rigid cupped member with upper outer wall having an inturned edge and seated in said aperture in the cupped member, an elastic ring mounted in said aperture with an outer wall part inwardly curvate to be engaged with the inner edge part of the cup member, and also having an inner upwardly directed ring part elastically embracing the traversing part of the pump rod releasably to prevent leakage therebetween, a tubular channel delivering outwardly from the first mentioned cupped member, a threaded plug, hollow, and threaded into the lower end part of the cupped member, a supply pipe having its upper end threaded and fitted within an interior thread of the plug, a delivery nipple threaded into and through a side part of the upper body wall device on the cupped member, and a non-rusting liner tube fitted removably within the body housing above the apertured medial plate between the housing and said cupped member.

3. In a pump of the character described, a tubular housing with an apertured top closure, a reciprocating pump rod traversing said closure and housing, an imperforate piston fixed on the upper inner part of the rod, an upwardly cupped rigid member positioned below and in spaced relation to the lower end of the housing, and having a central opening traversed by said rod, a depending pipe seated in said opening, a rigid plate mounted upon said cupped member, an elastic member and the rigid plate being clamped peripherally together between the adjacent faces of the housing and the cupped member, an internal housing member, tubular and having a plurality of side wall apertures therein, and rigidly removably mounted between the bottom part of the cupped member and said rigid plate, a flanged tubular valve member slidably mounted on the pump rod within the housing member, an elastic ring mounted on the valve member contacting its flange, said valve member being removably engaged with said internal housing member, elastic means mounted on the valve member and having an upturned inner rim to slidably yieldably engage the pump rod, and a delivery spout device in communication with the internal housing member.
